(57) CLAIM

The ornamental design for a chemical vapor deposition wafer carrier with thermal cover, as shown and described.

DESCRIPTION

FIG. 1 is a perspective view of a chemical vapor deposition wafer carrier with thermal cover, showing our new design.

FIG. 2 is a top plan view thereof.

FIG. 3 is a right side view thereof, with the left side view, front view, and rear view being identical.

FIG. 4 is a bottom plan view thereof; and,

FIG. 5 is a perspective view of the thermal cover of the chemical vapor deposition wafer carrier with thermal cover, shown separately for ease of illustration.

The broken lines in FIG. 4 form no part of the claimed design.
